HOG-RINGING TOOL

Dickie De Neui, Grundy County, Iowa

Application September 15, 1932
Serial No. 633,320

2 Claims. (Cl. 128—332)

My invention relates to improvements in hog-ring tools, and the object of my improvement is to supply a device of this class which will resiliently grasp under tension and clamp an open 5 split ring, thus preventing escape and loss of the ring at any time, particularly during the operation of ringing an animal.

I have accomplished this object by the means which are hereinafter described and claimed, and 10 which are illustrated in the accompanying drawing, in which Fig. 1 is a plan view of one face of a hog ringer constructed according to my invention, with portions of its jaws broken away, and shown as clamping in its jaws an open split ring. Fig. 2 is a fragmentary side elevation of the pivotally 15 connected jaws of said tool with portions of their handles, parts being broken away.

The tool shown is of a well-known pattern aside from its special pintle and resilient means combined therewith for keeping its jaws under clamping tension while holding an inserted open split ring 8. The ring is inserted in like facing longitudinal troughs or recesses 7 in the inner walls of the jaws 5 and 6. These jaws have flattened and 25 offset shanks 3 and 4 respectively, stopped at their offsets as usual, and both apertured in line centrally to seat therethrough a pintle rivet 9. One end part of this pintle is enlarged cylindrically at 10 and having its shoulder engaging the shank 3, and the other end part of the pintle which projects beyond the shank 4 is upset in engagement 30 therewith to secure the shanks together while allowing them free play relative to each other.

The shanks 3 and 4 respectively have integral 35 handles 1 and 2, the jaw 5 of the shank 4 having a traversing hole 11 of small diameter and the handle 1 of the shank 3 having a like hole 12, both holes spaced a distance from the pintle 9. I have shown a rod spring having a medial two 40 ply coil 14, the arms 13 and 15 of the spring being terminally bent to the same side at 13' and 15' and traversing the holes 11 and 12 respectively and bent over at their tips to lock them in place, the coils 14 being seated upon the cylindrical enlargement 10 of said pintle 9. This arrangement 45 is best shown in Fig. 2.

It will be seen that the middle coils of the spring are held centrally upon the pintle part 10 for free shifting in tensioning or reaction of 50 the spring arms 13 and 15, while the arms are secured against displacement at their clinched ends.

An open split ring 8 is thus clamped between 55 the jaws 5 and 6 with the spring members 13 and 15 under tension, and preventing the escape of the ring from the clamping jaws during any hog ringing operation, either before, during or after it, or when the tool is dropped or laid down, as might be the case with an ordinary tool of this 60 type. This prevents loss of the escaped rings,

as might often occur when such operations take place in barns, or open grassy ground.

The small drill holes 11 and 12 are placed where there is no weakening of the tool members, as might be the case if at or near their crossings. 65 The cylindrical head 10 of the pintle being relatively large in diameter, prevents cramping action on the coils 14, which are free to contract or expand sufficiently when the arms 13 and 15 are tensioned or in reaction. 70

As the spring is mounted upon one face only of the tool, it is easily and quickly assembled therewith, or removed therefrom for replacement when necessary. As this type of spring may be placed upon any tool of the kind illustrated, or any 75 other device of this class for which it may be appropriate in use, the cost of so improving the tool is low, and repairs may be made with a minimum cost.

Having described my invention, what I claim 80 as new, and desire to secure by Letters Patent, is:

1. In a clamping tool, clamping members of like but reversed shape, apertured intermediate their ends in alinement, a pintle traversing said apertures to project endwise therefrom at both 85 ends, one end of the pintle being diametrically and cylindrically enlarged with a shoulder engaging the adjacent member of the tool, and the opposite end of the pintle being upset to engage the other member, said members having facing 90 clamping jaws, one jaw being transversely apertured, said members having handle parts and one handle being transversely apertured, and a rod spring having a medial coil seated around the enlarged cylindrical head of said pintle with its 95 arms bent in one direction, traversing said apertures in the jaw and handle aforesaid and clinched upon their opposite parts respectively to removably interlock therewith. 100

2. In a clamping tool, crossed members, each 105 comprising a handle part and a curvate jaw with a longitudinal groove to seat releasably a split ring, the members offset to fit together closely, and having alined bearing apertures at their crossing location, a pintle seated in said 110 apertures and having widened heads, one head being elongated laterally to serve as anchoring means, and a resilient member medially connected to said anchoring head and with oppositely directed arms which are respectively engaged with a jaw of one handle and with the handle of the other jaw. 115
